UNITED STATES PATENT OFFICE.

WILLIAM E. KARNS, OF PARKER'S LANDING, PENNSYLVANIA.

PACKING-RING FOR PUMPS.

SPECIFICATION forming part of Letters Patent No. 278,557, dated May 29, 1883.

Application filed February 10, 1883. (No model.)

To all whom it may concern:

Be it known that I, WILLIAM E. KARNS, of Parker's Landing, in the county of Armstrong and State of Pennsylvania, have invented certain new and useful Improvements in Packing-Rings for Pumps; and I do hereby declare that the following is a full, clear, and exact description of the invention, which will enable others skilled in the art to which it appertains to make and use the same, reference being had to the accompanying drawings, which form a part of this specification, and in which—

Figure 1 is a diametrical sectional view of my improved packing-ring for pump-pistons. Fig. 2 is a perspective view of the inner clamping-ring detached; and Fig. 3 is a perspective view of the complete packing-ring, seen from the under side.

Similar letters of reference indicate corresponding parts in all the figures.

In packing pump-pistons experience has demonstrated that where leather or rubber packing is used it is apt to be injured in pumps used for pumping hot liquids or salt-water, so as to be soon made unserviceable—in the one case by the "burning" or rotting of the packing through contact with the hot liquids, and in the latter by the shrinkage of the leather caused by the salt-water, which will cause the packing to leak unless frequently renewed.

My invention has for its object to overcome this inconvenience; and to this end it consists in the detailed construction of a packing-ring consisting of a body of duck or similar material, which is clamped between two rings in such a manner as to leave a projecting rim of the selvage free, substantially as hereinafter more fully described and claimed.

In the accompanying drawings, the letter A denotes the outside metallic ring, between which and the inner ring, B, the packing is clamped. This packing consists of a strip of duck or textile fabric of a similar nature, C, of such a length that it may be rolled up or coiled to form several layers, as shown at a, b, and c in Fig. 1, between the two rings A and B. The packing-strip is cut of such a

width that the selvage C' will project beyond the lower rim of the clamping-rings, the increased thickness of the material at the selvage forming a packing of several layers between the pump-piston and pump-barrel in which the piston works. The outer ring, A, is rounded at the top to form a bead, A', the sharp inner edge of which bites the fabric C, which at its upper end overlaps the bead B' of the inner ring, B. This in itself forms a good fastening for the packing between the two rings; but to still better hold it in place and prevent any possibility of its working loose, I crimp the inner ring, as shown at D in Fig. 2^b, so as to form ribs or ridges which bite into the fabric between the two rings. For this purpose the inner ring, B, is made flaring, as shown in Fig. 2^a, and of ductile metal, as, if made cylindrical, like the outer ring, it would be reduced in size by the process of forming the crimps or ribs D, so as not to hold or bite the packing as firmly as is desirable.

I do not confine myself to any particular means for fastening this ring upon the piston or plunger, as this may be done by bolting by means of clamping-screws, keys, or wedges, and in many other ways; but,

Having thus described my invention, I claim and desire to secure by Letters Patent of the United States—

A packing-ring for pump-pistons, consisting of the outer cylindrical ring or sleeve, A, packing C, of textile fabric, having a projecting selvage-rim, C', of several thicknesses, and flaring inner ring, B, crimped to form ribs or ridges D, biting sidewise into that part of the packing which is clamped between the two rings, substantially as and for the purpose herein shown and set forth.

In testimony that I claim the foregoing as my own I have hereunto affixed my signature in presence of two witnesses.

WILLIAM ELLIOTT KARNS.
